FIG.16.

FIG.17.

FIG. 1 is a top plan view of a camera, showing my new design;

FIG. 2 is a front elevational view of the camera of FIG. 1;

FIG. 3 is a bottom plan view of the camera of FIG. 1;

FIG. 4 is a left side elevational view of the camera of FIG. 1;

FIG. 5 is a right side elevational view of the camera of FIG. 1;

FIG. 6 is a rear elevational view of the camera of FIG. 1;

FIG. 7 is a front elevational view of the camera of FIG. 1 showing a modified embodiment thereof wherein the surface decorative treatment of the top and rear has also been applied to the front of the camera and wherein a somewhat modified electric eye opening is employed;

FIG. 8 is a left-side elevational view of the camera of FIG. 7;

FIG. 9 is a right-side elevational view thereof, the bottom and rear thereof being identical to the bottom and rear seen in FIGS. 3 and 6;

FIG. 10 is a top plan view of the camera of FIG. 1 showing a modified embodiment thereof wherein the flash actuator socket is a separable unit, the same being omitted herein;

FIG. 11 is a front elevational view of the camera of FIG. 10;

FIG. 12 is a left-side elevational view of the camera of FIG. 10;

FIG. 13 is a right-side elevational view thereof;

FIG. 14 is a view similar to FIG. 10, but showing the camera with the flash actuator socket in place;

FIG. 15 is a front elevational view of the camera and socket of FIG. 14;

FIG. 16 is a left-side elevational view of the camera and socket of FIG. 14;

FIG. 17 is a right-side elevational view of the camera and socket of FIG. 14.

The bottom and rear of the camera of FIGS. 10-17 are identical to those seen in FIGS. 3 and 6.

This is a continuation in part of my application Ser. No. D.86,101 filed July 9, 1965, now abandoned.

I claim:

The ornamental design for a camera, as shown and described.
